FIG. 2

FIG. 3

INVENTOR

E. G. Hutterer

BY
Milton S. Crandall,

ATTORNEY

UNITED STATES PATENT OFFICE.

EDWARD G. HUTTERER, OF SANBORN, IOWA.

TRUSS.

1,381,123.

Specification of Letters Patent. Patented June 14, 1921.

Application filed January 24, 1920. Serial No. 353,678.

To all whom it may concern:

Be it known that I, EDWARD G. HUTTERER, a citizen of the United States, and a resident of Sanborn, in the county of O'Brien and State of Iowa, have invented certain new and useful Improvements in Trusses, of which the following is a specification.

My invention has for its primary object the production of an improved means for 10 reducing abdominal hernias.

A further object of the invention is the production of a hernia truss embodying certain novel features of construction and arrangements of parts for forcing the viscera into and holding it within its natural cavity.

Furthermore, the invention contemplates a hernia truss embodying a pad and co-acting parts which hold the viscera within its 20 natural cavity and tend to contract the inguinal ring to facilitate healing of the tissues.

Still another object of the invention is the production of a hernia truss thoroughly efficient in use and which may be applied and worn with the least inconvenience and discomfort.

The above and other objects and advantages I successfully attain in the embodiment hereinafter described, defined in the appended claim, and illustrated in the accompanying drawings, which form a part of this application, and in which like characters of reference indicate corresponding parts throughout the several views, of 35 which,

Figure 1 is a perspective view of a truss constructed in accordance with the invention;

Fig. 2 is an enlarged rear elevation of the pad; and Fig. 3 is a central horizontal section thereof.

While I have illustrated, and hereinafter described the preferred embodiment of the invention, I would not be understood as being limited to such specific construction, for many variations and modifications may be made in the details of construction and arrangement of parts herein disclosed, without departing from the spirit and scope of

the invention, as defined in the appended claim.

Referring now to the illustrations, the pad includes a disk, 4, of rubber or other suitable elastic sheet material provided on opposite sides with ears, 5, and a depending part, 6. One of the ears, 5, is suitably secured, as at 7, to one end of a belt, 8, adapted to encompass the body, and detachably and adjustably secured at its other end to the other ear, 5, 60 as by a suitable buckle 9. 10 is a strap having one end looped, as at 11, to slide upon the rear portion of the belt. The strap, 10, is adapted to be passed between the limbs of the wearer and is detachably and adjustably secured at its forward end to the ear, 6, as by a buckle, 11, or otherwise. On the rear of the disk, 4, is mounted a pneumatic ring, 12, secured to the disk, 4, by an annular rib, 13, vulcanized to the disk and to 70 the face of the ring, 12, adjacent the periphery of the latter.

The ring, 12, removably incloses a circular pad including the inner and outer walls, 14, interconnected at their edges. Between 75 the walls, 14, is inserted hair, 15, or other suitable soft padding. The said circular pad rests against the disk, 14.

In application it is obvious that the pad is so positioned that the ring, 12, is disposed centrally of the inguinal ring, then as the disk projections, 5, are stretched and disposed slightly rearwardly, it is evident the tubular ring will be rolled inwardly as indicated by the arrow and dotted lines in Fig. 85 3, thus tending to slightly contract the diameter of the ring, and as the rear face of the ring bears against the body of the wearer it is evident the said contraction of the ring will tend to contract the inguinal ring and 90 hold the same against retraction or straining of the tissues caused by exertion of the patient.

Having thus described my invention, what I claim as new and desire to secure by Letters Patent of the United States is,—

A trusspad including an elastic sheet, an elastic ring, circular in cross-section and adjacent the sheet, a thin circular web securing the sheet to the adjacent side of the 100

ring whereby the ring may be rolled inwardly, a circular soft pad encircled by the ring and including inner and outer walls having their edges secured together to provide a pad which is thin at its periphery, the pad being so constructed and related to the ring that the intermediate portion of the pad extends approximately to the plane of

the outer side of the ring, and the peripheral edge of the pad is positioned substantially 10 midway between the sides of the ring, to permit inward rolling of the ring.

In testimony whereof I have hereunto set my hand this 16 day of January, 1920.

EDWARD G. HUTTERER.
